CUTTER FOR SHEET MATERIAL

Charles C. Patton, Port Caledonia, Nova Scotia, Canada

Application December 1, 1952, Serial No. 323,377

4 Claims. (Cl. 164—42)

This invention relates to cutters for sheet material, either hand or power operated, for example, a cutter such as is described in my United States Patent No. 2,563,741, which was granted on August 7, 1951.

While a cutter such as is described in the patent mentioned above operates satisfactorily, I have made the discovery that the action of stripping the material from the blade can be greatly improved by provision of a stripper-bar operated jointly by the cutter blade and a pivot-plate arranged to pivot about a point spaced from the pivot point of the blade so that the pivot-plate pivots in substantially the same plane as the blade.

According to the present invention a cutter comprises two bolster plates defining a cutting plane, a blade pivoted adjacent one end thereof at a first pivot point between the bolster plates so as to pivot forwardly for a cutting stroke, a pivot-plate pivoted adjacent one end thereof at a second pivot point spaced from the first pivot point so that the blade and the pivot-plate when pivoted move in substantially the same plane, a link pivotally joining the blade and the pivot-plate at points spaced lengthwise of the blade and the pivot-plate at substantial distances from the first and second pivot points, and a stripper-bar pivotally joining the blade and the pivot-plate and extending past the blade to engage the upper side of the work to be cut as the blade is raised following a cutting stroke, the stripper-bar being pivotally and slidably connected to the pivot plate above and rearwardly of the second pivot point and being pivotally connected to the blade at a point on the blade above and rearwardly of the first pivot point.

In a preferred form of the invention the pivot-plate, which is required in the operation of the stripper-bar, is another blade operating between bolster plates so that two cutters are provided, one of which can be set for one material while the other is set for another material. For example, one cutter can be operated with little or no clearance between the blade and the bolster plates as is desirable for cutting steel, while the other blade may have a suitable clearance from the bolster plates for cutting a crushable material such as asbestos.

It is also preferred in accordance with the present invention to provide a pair of set screws in the bolster plates each of which is adjustable into the space between the bolster plates and is located to make contact with the back edge of the blade when it is raised from its cutting position so that upon the back of the blade coming between the set screws the bolster plates are spread apart thereby tending to spread apart the cut material and so freeing the blade so that the material can be pushed ahead for a new cut. An important advantage of a stripper-bar in accordance with the present invention is that as the blade is raised from the cutting position the stripper-bar has a sliding motion against the material to be cut so helping in moving the material ahead for the next cut.

Another advantage of a cutter having a stripper-bar in accordance with the present invention is that the stripper-bar is effective in stripping material from the blade as soon as the blade is raised from its full-cut position.

The stripper-bar may be conveniently adjusted for various materials and can be arranged to operate with either blade in the embodiment of the invention in which the pivot-plate is another cutter blade.

5 The invention will be further described with reference to the accompanying drawings in which:

Figure 1 is a perspective view of a cutter according to the present invention;

Figure 2 is a cross sectional view of the cutter shown in Figure 1, taken on the line II—II at a larger scale;

Figure 3 is a cross sectional view of the cutter shown in Figure 1, taken on the line III—III at a larger scale; and

Figure 4 is a side elevation of the cutter shown in Figure 1 with the blades in full-cut position, and at a larger scale.

Referring to the drawings, the cutter shown comprises two pairs of bolster plates 10A, 10B and 11A, 11B which are fastened to base plates 12, 13. The base plates 12, 13 are fastened to a base 14.

20 The bolster plates 10A, 10B and 11A, 11B are suitably bored to accommodate pivot pins 15A and 15B upon which pivot the blades 16A and 16B about suitable pivot holes formed therein. A handle member H is secured to the outer end of the blade 16A by bolts 18. The handle H is connected to the blade 16B by links 17 which are pivotally connected to the blade 16B by a bolt 18.

A pair of stripper-bars 19 are pivotally connected to the blade 16A by a bolt 20A (Figures 1 and 4) at a point above and rearwardly of the pivot point for the blade 16A formed by the pin 15A. The stripper-bars 19 are pivotally and slidably connected to the blade 16B by a bolt 20B at a point above and rearwardly (with respect to the blade 16A) of the pivot point of the blade 16B formed by the pin 15B. Provision for sliding of the links 19 relative to the blade 16B is made by slots 21 (Figure 4) in the links 19. Two slots 21 are provided in each link 19 for which the reason will be explained below.

Two set screws 22A, 22B are provided near the rear of the bolster plates 10A, 10B in positions such that when the blade 16A is raised from its cutting position, as shown in Figure 1, the back edge of the blade comes between the set screws 22A, 22B (see Figure 2) causing the bolster plates 10A and 10B to be spread apart an amount dependent on the adjustment of the set screws 22A, 22B. This spreading apart of the bolster plates 10A, 10B is provided for by spring washers 29A, 29B on the pin 15A. As shown in Figures 3 and 4, the blade 16B has clearance with the bolster plates 11A, 11B as determined by a pair of washers 23A, 23B on the pin 15B. This clearance can be set by using washers 23A, 23B of different thicknesses and at the same time making a similar adjustment at the spacer 24B provided at the other end of the bolster plates 11A, 11B. A spacer 24A is also provided for the bolster plates 10A, 10B. The bolster plates 10A, 10B and 11A, 11B are of heavy material and are bevelled at a suitable angle over their working portions 25A, 25B and 26A, 26B. The bolster plates are undercut throughout their length by cuts 27A, 27B and 28A, 28B to provide clearance for the blade and waste cuttings.

60 The cutter shown in the drawings is set so that the blade 16A has the bevelled edges 25A, 25B of the bolster plates 10A, 10B pressed against it by the spring washers 29A, 29B (Figure 2), while the blade 16B has the bevelled edges 26A, 26B of the bolster plates 11A, 11B spaced from it by the washers 23A, 23B (Figure 3). With these settings for the blades, the blade 16A can be used to cut such materials as steel, and the blade 16B can be used to cut such materials as asbestos sheeting. The handle H is shown on the blade 16A as required for cutting steel, but when cutting asbestos it may be connected directly to the blade 16B.

When cutting sheet metal with the blade 16A, the sheet metal is placed across the bolster plates 10A, 10B with the blade 16A in fully raised position. The cut is then commenced and as the cut proceeds, the sheet metal rides down on the bevelled edges 25A, 25B of the bolster plates 10A, 10B thereby slightly spreading the edges of the cut to prevent binding on the blade. At the same time the stripper-bars 19 move downward to engage the sheet metal in the manner indicated in Figure 4. On completion of the cut the blade 16A is frictionally engaged by the edges of the cut in the sheet metal and, therefore, raising the blade 16A tends to raise the sheet metal from the bolster plates 10A, 10B causing even greater frictional engagement between the blade 16A and the edges of the cut in the sheet metal. This frictional engagement tends to lift the sheet metal as the blade 16A is raised but the stripper-bars engage the sheet metal firmly and at the same time, slide against the sheet metal in a direction to aid in moving the sheet metal toward the blade 16A for the next cut. The relative movement between the stripper-bars and the cutting edge of the blade 16A causes the sheet metal to be engaged by the stripper-bars. As the cutting edge of the blade 16A pivots to a vertical position, as shown in Figure 1, the stripper-bars provide a wiping action along the cutting edge of the blade 16A which causes the sheet metal to be stripped from the blade. As the blade 16A reaches a vertical position (Figures 1 and 2) its back edge presses between the set screws 22A, 22B causing the bolster plates to spread apart thus relieving binding between the sheet metal and the blade.

As shown in Figures 1 and 4, the stripper-bar 19 is provided with slots 21 for making pivotal connection to the bolt 20B. The shape of the slot 21 provides for sliding of the stripper-bar 19 relative to the blade 16B so that the pivoting movement of the blades 16A and 16B will not be locked because of the stripper bar 19 not being parallel to the link 17, as would be required for true parallelogram motion. In the case of the stripper bar being parallel to a line between the pins 15A and 15B, the slots 21 would not be required but less effective stripping action would be provided at the cutting edge of the blade 16A.

The blade 16B is used for cutting sheet asbestos and like materials. The handle H is connected to the blade 16B and the stripper bars are moved so that the bolts 20A, 20B engage the slot and hole which are shown as unoccupied in the drawings (Figures 1 and 4). When cutting asbestos, the action of the stripper bars 17 is the same as that described in connection with cutting sheet metal.

In constructing a cutter having stripper-bar action in accordance with the present invention, a single stripper-bar

could be used, but a stronger cutter results by using a pair of stripper-bars as shown in the drawings. It is not necessary to have a blade 16B arranged to cut another material, although this arrangement is of advantage. A plain pivot plate could be substituted for the blade 16B without interfering with the operation of the blade 16A and the stripper-bars 19. If desired the cutter may be power-operated, for example, by a motor and speed-reducing gears.

What I claim as my invention is:

- 10 1. A cutter for sheet material comprising two bolster plates defining a cutting plane, a blade having a cutting edge and pivoted adjacent one end thereof at a first pivot point between the bolster plates so as to pivot forwardly with said cutting edge toward the bolster plates for a cutting stroke, a pivot-plate pivoted adjacent one end thereof at a second pivot point spaced from the first pivot point so that the blade and the pivot-plate when pivoted move in substantially the same plane, a link pivotally joining the blade and the pivot-plate at points spaced lengthwise of the blade and the pivot-plate at substantial distances from the first and second pivot points, and a stripper-bar pivotally joining the blade and the pivot-plate and extending past the cutting edge of the blade to the upper side of the sheet material work to be cut as the blade is raised following a cutting stroke, the stripper-bar being pivotally and slidably connected to the pivot plate above and rearwardly of the second pivot point and being pivotally connected to the blade at a point on the blade above and rearwardly of the first pivot point.
- 20 2. A cutter as defined in claim 1 comprising a pair of stripper-bars arranged with one on either side of the blade.
- 30 3. A cutter as defined in claim 1 in which the stripper bar has a slot-shaped opening through which it is pinned to the pivot plate so as to provide for sliding between the stripper bar and the pivot plate.
- 35 4. A cutter as defined in claim 3 in which the stripper-bar makes an acute angle with a straight line drawn between the first and second pivot points so that the stripper-bar slopes toward the cutting plane defined by the two bolster plates.
